UNITED STATES PATENT OFFICE.

LEONARD GUTEKUNST, OF PHILADELPHIA, PENNSYLVANIA.

COVER SUPPORT.

Application filed March 22, 1928. Serial No. 263,654.

This invention relates generally to certain new and useful improvements in supports for hinged covers, lids and the like, and more particularly to a form of support arranged to automatically lock the cover or lid in raised position at the same time it readily permits the cover to be released from its locked position in order that said cover may be lowered into closed position.

10 While the present invention is particularly adapted for holding the cover or lid of a stage-lighting box in opened position, it will be understood, of course, that it is equally applicable for use in connection with the 15 hinged covers or lids of phonographs, refrigerators, trunks and other such cases or boxes, and, in fact, wherever it is desirable to automatically lock a hinged cover in raised position, release of the cover from this locked 20 position being readily and solely accomplished by manipulation of the cover itself independently of and without separate manipulation of the support.

It is accordingly one of the primary objects of this invention to provide a device for 25 supporting a hinged cover in raised position, said device being not only simple in construction and strong and durable in use, but being also operable to automatically lock the cover 30 when the latter is raised to a predetermined height.

A still further object of the invention is the provision of a device of the character mentioned which will automatically assume a 35 supporting position when the cover is raised to a predetermined height, and which will be automatically released from said supporting position when the cover is raised to a still further height whereupon the cover may be 40 lowered into closed position.

A still further object of the invention is the provision of a support for a hinged cover which is arranged to be automatically locked in position to hold said cover open and which 45 when released from said locked position permits the cover of its own weight to be lowered into closed position, the support being inoperative to maintain said cover in raised position after it has been released from said 50 locked position.

A still further object of the invention is the provision of a device for supporting a hinged cover in raised position, said device including an arm pivotally secured to the cover and 55 a guiding means with which the free end of said arm is operatively associated, said means

being operative to cause the free end of the arm to describe a closed loop as the cover is raised to opened position and then lowered into closed position.

60 A still further object of the invention is the provision of a hinged cover support which is composed of relatively few parts and which is adapted for efficient use in connection with various types and forms of hinged 65 covers or lids.

Other objects and objects relating to details of construction and operation will appear more fully hereinafter.

The invention consists substantially in the 70 construction, combination, arrangement and relative location of parts, all as will be described more fully hereinafter, as shown in the accompanying drawings, and as finally pointed out in the appended claims. In the 75 said accompanying drawings, wherein the supporting device is shown in operative association with the hinged cover of a stage lighting box, the latter being shown and described for illustrative purposes only:

80 Figure 1 is a perspective view of the box showing the cover or lid thereof supported in raised position;

Figure 2 is a cross sectional view of the box showing a portion of the supporting device, 85 the cover in this instance being closed;

Figure 3 is a view similar to Figure 2 showing the supporting device in locked position for supporting the cover in raised position;

Figures 4 to 8, inclusive, are views respectively showing the supporting device in various positions as the cover is raised to opened position and then lowered into closed position; and

Figure 9 is a cross section through the supporting device taken on the line 9—9 of Figure 4.

95 Referring more particularly to the drawings, it will be seen that the invention has been shown in connection with a stage-lighting box 10 provided with a cover 11 which is hinged, as at 12, to the box. Secured to the under surface of the cover 11 in any suitable manner is a battery of lamps 13, these lamps being so arranged that when the cover is 100 raised by means of the handle 14 to the position shown in Figures 1 and 3 the light rays emanating therefrom will be projected upon the stage. In the usual practice, the box 10 constitutes one of a series of similar boxes 105 arranged end for end along the front of the stage and in such manner that the lamps are 110

directed toward the rear thereof, but inasmuch as this arrangement forms no part of the present invention it is not believed necessary to describe it in greater detail.

5 The device for supporting the cover in normal raised position is designated generally in Figures 1 to 3 by the numeral 15 and comprises generally an arm or pitman 16 operatively associated with a bracket 17. This arm 10 or pitman is pivotally secured, as at 18, to the cover 11, preferably to the under surface thereof just inside its side edge. The free lower end of the pitman 16 is provided with a laterally projecting stud or pin 19 upon 15 which is preferably received a roller 20. As appears clearly in the drawings, this stud 19 projects outwardly toward the side wall 21 of the box 10.

Secured to the box 10, preferably to the 20 side wall 21 thereof, is the bracket 17 which is arranged for operative association with the stud 19. This bracket 17 comprises a main body member or plate 22 provided along its upper edge with a flange 23 arranged to be 25 secured in any suitable manner to the under surface of the inturned upper edge 24 of the box 10, it being understood, of course, that said plate may be secured to the side 21 or upon the bottom of the box, if desired. The 30 illustrated arrangement, however, is preferred due to the fact that it makes possible the employment of a standard length pitman which is not affected by changes in depth of the box. Formed along the lower edge of 35 the plate 22 is a flange 25, this flange constituting a runway which is inclined rearwardly and upwardly toward the hinged edge of the cover. Continuing upwardly from the upper 40 end of flange 25 is a substantially vertically extending flange 26, the lower and upper ends of which are curved to provide vertically spaced seats 27 and 28, the seat 27 being depressed somewhat below the plane of the runway 25. Interconnecting the upper seat 28 45 and the forward and lower end of the runway 25 is an arcuately shaped flange 29, the forward and lower end thereof forming conjointly with the similar end of the runway 25 a third seat 30, this latter seat being arranged considerably in advance of and at an 50 elevation considerably lower than either of the seats 27 and 28. It will be noted that the flanges 25, 26, and 29 are preferably formed as integral continuations one of the other 55 such that they constitute a closed loop having the three spaced seats 27, 28 and 30, each of which project somewhat beyond the perimetral boundary of the loop.

Pivotaly mounted within the area defined 60 by the flanges 25, 26 and 29 is a pawl or similar member 31, the forward end of this pawl being pivotally supported upon a pin 32 projecting inwardly from the main body member or plate 22. This pawl 31 is of the particular shape shown in the drawings wherein

it will be seen that the upper and lower edges thereof are each arcuately shaped and that they diverge toward the rear end to form an obtuse heel portion 33 and an acute toe portion 34 interconnected by the substantially straight rear edge 35. This pawl 31, which is preferably of a uniform thickness substantially equal to that of the flanges 25, 26 and 29, is of a length and is so arranged that the rear edge thereof normally overlies the seat 70 or depression 27 provided at the upper end of the runway 25. When in this position (see Figures 3 and 4) it will be seen that paths of travel for the stud are respectively provided between the lower edge of the pawl and the flange 25 and between the upper edge of the pawl and the flange 29. It is within these paths that the laterally projecting stud 19 travels as the cover is raised to opened or lowered into closed position. 80

When the parts are assembled and the cover is closed, the stud 19 is positioned within the seat 30 located at the lower end of the runway 25 while the pawl 31 is in its lowermost position (see Figure 4). As the cover is raised about the hinges 12, the arm or pitman 16 is lifted and in so doing causes the stud 19 to travel upwardly along the inclined runway 25 until it reaches a point immediately above the seat 27 within which the stud automatically seats due to the weight of the cover. The pawl 31, being free to move upwardly about its pivot, offers no resistance whatever to this upward travel of the stud, the final position of the pawl being that shown in Figure 5 when the stud is seated within the seat 27 such that the arm is locked in cover-supporting position. 90

In order to release the cover from its locked open position, it is merely necessary to raise 105 it slightly above its normal raised position whereupon the stud 19 will be lifted vertically from the seat 27 toward the seat 28. During this operation, the pawl 31 will also be raised, the stud first engaging the heel portion 33 and then the toe portion 34 thereof. (See Figures 6 and 7.) At the instant the stud is lifted into the seat 28, the toe portion 34 of the pawl passes beneath the stud, and the pawl, being no longer in engagement with the stud, drops into the position shown in Figure 7, it being observed that this position is exactly similar to that shown in Figure 4. In this final position of the pawl, the upper edge thereof constitutes a forwardly and downwardly extending runway along which the stud 19 travels when the cover is lowered to again assume the position shown in Figure 4. In Figure 8, the stud is shown midway between the seats 28 and 30 as it travels downwardly from the former toward the latter. Due to the fact that when the pawl is in its lowermost position, the toe portion 34 thereof abuts against the flange 26, there is no possibility of the stud falling vertically into the 110 120 130

seat 27, the only path of travel for the stud being that which is defined by the upper edge of the pawl.

It is to be understood, of course, that various changes and modifications of the invention may be made from time to time without departing from the real spirit or principles thereof, and it is therefore intended to claim the same broadly as well as specifically as defined in the appended claims.

What is claimed as new and useful is:

1. In a support for a hinged cover or the like, in combination, an arm pivotally secured to and depending from said cover, said arm being provided at its free end with a laterally projecting stud, and a bracket supported independently of said cover and arranged for operative engagement with said stud, said bracket including an inclined runway having a seat at the upper end thereof for reception of said stud when the cover is raised to a predetermined height and a seat at its lower end for reception of said stud when the cover is in closed position, and means extending between said seats and normally overlying the upper seat for preventing said stud from regaining said upper seat when the cover is raised to a greater height.

2. In a support for a hinged cover or the like, in combination, an arm pivotally secured to and depending from said cover, said arm being provided at its lower end with a laterally projecting stud, a bracket supported independently of said cover and including an upwardly inclined runway, the opposite ends of which terminate in depressions arranged to respectively receive said stud when the cover is raised to a predetermined height or is in closed position, and a member pivotally secured to said bracket the free end of which normally overlies the upper depression, said member constituting a downwardly inclined runway terminating immediately above the lower depression and along which said stud is arranged to travel when the latter is lifted out of said upper depression.

3. In a support for a hinged cover or the like, in combination, an arm pivotally secured to and depending from said cover, said arm being provided at its lower end with a laterally projecting stud, a bracket operatively associated with said stud and comprising a plate provided with an upwardly inclined flange the upper end of which terminates in a vertically extending flange, a seat formed at the juncture of said inclined and vertically extending flanges, said seat being arranged to receive said stud when the cover is raised to a predetermined height, and a member pivotally secured to said plate at a point adjacent the lower end of said inclined flange, the free end of said member being arranged to normally overlie said depression and the lower pivoted end thereof being spaced from said inclined flange to

provide a passage between said pivotal point and said flange for said stud as said cover is lifted.

4. In a support for a hinged cover or the like, in combination, a bracket comprising a main member provided at its lower edge with an upwardly and rearwardly inclined flange and at its rear edge with a substantially vertically extending flange constituting an integral continuation of said inclined flange, an arcuately shaped flange extending between and integrally joining the lower end of said inclined flange with the upper end of said vertically extending flange, a member pivotally supported upon said plate at a point located within the area defined by said flanges, the pivoted end of said member terminating short of the juncture formed between said inclined and arcuately shaped flanges and the free end thereof being arranged to abut against said vertically extending flange, the upper and lower edges of said pivoted member being divergent toward the free end thereof.

5. In a support for a hinged cover or the like, in combination, an arm depending from said cover and having a stud on the lower end thereof, a bracket including a plate having an upwardly inclined runway along which said stud is arranged to travel as said cover is being raised, said runway being provided at its upper end with a depression arranged to receive said stud whereby to lock said arm in cover-supporting position, a pawl pivotally secured to said plate such that the free end thereof normally overlies said depression, the upper edge of said pawl constituting a downwardly inclined runway for said stud, and a flange extending vertically from the upper end of said upwardly inclined runway, the free end of said pawl being arranged to normally abut against said flange in overlying relation with respect to said depression when said cover is in closed position and being shiftable away from said flange and upwardly of said depression when said cover is raised to a predetermined height.

6. In a support for a hinged cover or the like, in combination, an arm depending from said cover and having a stud on the lower end thereof, a bracket supported independently of said cover, said bracket being provided with an upwardly inclined runway along which said stud is arranged to travel as said cover is being raised, a socket at the upper end of said runway within which said stud is received to lock said arm in cover-supporting position, a flange extending vertically above said socket to form a second socket vertically spaced above said first socket, a pivotally supported member arranged with the free end thereof overlying said first socket and in abutting relation with respect to said flange, said member being shiftable upwardly about its pivot to permit said stud to pass

freely into said first socket and thence upwardly toward said second socket.

7. In a support for a hinged cover or the like, in combination, an arm depending from said cover and having a stud on the lower end thereof, an upwardly inclined runway along which said stud is arranged to travel as said cover is raised, a pair of vertically spaced sockets arranged at the upper end of said runway, and a pivotally mounted member the upper edge of which constitutes a downwardly extending runway along which said stud is arranged to travel as said cover is lowered and the free end of which is arranged to nor-

mally overlie the lower of said sockets, said member being shiftable upwardly to permit said stud to seat first in said lower and then in the upper of said vertically spaced sockets, said member being further arranged to automatically drop into a position such that said upper edge thereof lies below said stud when the latter passes into said upper socket whereby to prevent said stud from reseating in said lower socket.

In testimony whereof, I have hereunto affixed my signature.

LEONARD GUTEKUNST.
